UNITED STATES PATENT OFFICE.

ALFRED A. RUTTAN, OF ROCHESTER, NEW YORK.

SAW-GUARD.

1,140,400.

Specification of Letters Patent. Patented May 25, 1915.

Application filed July 22, 1912. Serial No. 710,850.

To all whom it may concern:

Be it known that I, ALFRED A. RUTTAN, of Rochester, in the county of Monroe and State of New York, have invented certain new and useful Improvements in Saw-Guards; and I do hereby declare the following to be a full, clear, and exact description of the same, reference being had to the accompanying drawings, forming a part of this specification, and to the reference numerals marked thereon.

My invention relates to saw guards, and it has for its object to provide a guard that is capable of ready adjustment transversely of the cutting plane of the saw, and the movement of which in the direction of the plane of the saw may be adjustably limited.

Another object of my invention consists in arranging the parts in such a manner that the guard is rigidly supported on the saw table in a manner so as to effectually prevent it from losing its proper relation to the saw.

Still a further object of my improvement resides in the provision of means for throwing the guard upwardly away from the saw when not in use, and locking it in such upper position, and also the devices for limiting its downward movement for use with different styles of work, where it must be arranged at varying elevations above the saw.

To these and other ends the invention consists in certain improvements and combinations of parts, all as will be hereinafter more fully described, the novel features being pointed out in the claims at the end of the specification.

In the drawings: Figure 1 is a side elevation, partly in section, of a saw table embodying a preferred arrangement of my invention; Fig. 2 is a view in front elevation of the same; Fig. 3 is a side elevation, showing the guard in raised position; Fig. 4 is a detail plan view, and Fig. 5 is a sectional view on the line 5^a—5^a of Fig. 4.

Similar reference numerals throughout the several figures indicate the same parts.

With these objects in view, my invention preferably comprises a saw table 1, provided with the rotary saw 2 arranged therebeneath in the usual manner. The guard is mounted on the table, preferably in the manner that will now be described, and to this end I provide posts 3 which are threaded or otherwise attached to the saw table, and are slotted at their upper ends, as indi-

cated at 4, to provide bearings for the guard support that will be described hereinafter. The guard is designated at 5, being secured to the forwardly extending arm 6 which constitutes a portion of the guard support designated at 7. The guard support is preferably in the form of a T-shaped bar or rod, as shown, being provided with cylindrical end portions 8 which engage the slotted posts 3 and are rotatable therein. By this means, the guard is thrown toward the saw when in use, and moved upwardly as shown in Fig. 3 when not in use. In order to limit the downward movement of the guard, to vary its height for different styles of work, there is preferably provided an extension 9 on one of the posts 3, said extension having a threaded opening therein which receives the threaded pin 10, the latter being operated by a knurled head 11 and held in adjusted position by means of the lock nut 12. The pin constitutes an adjustable stop, which is engaged by the arm 13 formed on the guard support. By moving the adjustable stop upwardly or downwardly, the movement of the guard support is correspondingly controlled, thereby permitting the guard to be moved closer to or farther from the saw, as desired. In order to hold the guard in its upward position when not in use, the extension 9 has attached thereto a downwardly projecting leaf spring 14 which engages the upper face of the arm 13, as shown in Fig. 3, holding the guard support raised until the spring is released.

The support may be held in position on the post in any suitable manner, as for instance, by means of cotter pins 15. In order to adjust the saw guard in a direction transversely to the plane of the saw, I employ means for permitting the support to be adjusted longitudinally and holding it in such adjusted position. To this end, I preferably provide a series of washers or spacing plates 16, arranged between one end of the support and the corresponding post 3. To adjust the support longitudinally, the washers are removed and transferred to the opposite end of the support, being there disposed between the other post and the corresponding end of the support. By changing the number of washers at the respective ends of the support, the desired adjustment can be accurately obtained, and the guard is thus held fixed in proper relation to the saw.

17 designates a spreader attached to the

guard at the rear edge thereof, and extending downwardly to a point in rear of the uppermost point of the saw, so as to engage the work in the cut produced by the saw, and 5 separate the strips. By attaching the spreader to the guard, it is rigidly held, and can be accurately retained in proper position relatively to the work. It will be apparent that if the guard is too low for the 10 work, or an unusually thick piece of work is inserted, the guard will be raised away from the saw by contact with the top of the work, its weight being sufficient to hold it in normal position as shown in Fig. 1.

15 While I have shown and described a particular arrangement of my invention, it is to be understood that I am not limited to the precise construction disclosed as I believe it to be new to provide for adjusting a saw 20 guard in a direction transverse to the plane of the saw, and for adjustably limiting the movement of the guard toward the saw, and I desire to cover by this application any 25 modifications or departures that may come within the scope of the claims hereinafter.

I claim as my invention:

1. The combination with a saw table, of a pair of vertically arranged posts mounted thereon in spaced relation to each other, a horizontally disposed support pivotally arranged on said posts, a guard rigidly carried by said support, and adjustable means for limiting the rotative movement of the support.
- 30 2. The combination with a saw table, and a rotary saw arranged therebeneath, of a

support pivotally mounted on the saw table and adjustable in a direction transverse to the cutting plane of the saw, adjustable means for limiting the movement of the support in the direction of the plane of the saw, and a guard rigidly carried by the support.

3. The combination with a saw table, of a pair of vertically disposed posts mounted thereon in spaced relation to each other and provided with bearings, a horizontally disposed support mounted in said bearings, and adjustable in the direction of its length, the support being rotatable in said bearings, an 45 adjustable stop carried by one of said posts, an arm on the support adapted to engage said stop, and a guard rigidly mounted on the support.

4. In combination with a saw table, a pair 50 of vertically disposed posts mounted thereon in spaced relation to each other and provided with bearings arranged above the table, a horizontally disposed support rotatably mounted in said bearings, the support 60 being adjustable in said bearings in the direction of its length or transversely of the plane of the saw, a guard rigidly mounted on the support intermediate the ends thereof, an adjustable stop arranged on one of the 65 posts, and an arm or extension on the support having engagement with said stop.

ALFRED A. RUTTAN.
